UNITED STATES PATENT OFFICE.

MAXIMILIAN KLAIBER, OF BROOKLYN, NEW YORK, ASSIGNOR, BY DIRECT AND MESNE ASSIGNMENTS, TO AUTO SLYDE & MOVING PICTURE MACHINE CO., INC., A CORPORATION OF NEW YORK.

STEREOPTICON APPARATUS.

1,349,725.

Specification of Letters Patent. Patented Aug. 17, 1920.

Application filed August 7, 1916. Serial No. 113,464.

To all whom it may concern:

Be it known that I, MAXIMILIAN KLAIBER, a citizen of the United States, and a resident of Brooklyn, county of Kings, State of New York, have invented certain new and useful Improvements in Stereopticon Apparatus, of which the following is a specification.

This invention relates to a mechanism wherein pictures are projected, mechanically, upon a screen or wall, or like medium, the device being, preferably, power driven, as by an electric motor, and wherein a series of pictures are brought into alinement above an electric lamp and a condenser and beneath a projecting lens, a predetermined lapse of time between the exposure of each picture of the series being preferably provided for.

One of the objects of my invention is to produce a device of this kind which is simple in construction and permits a comparatively great number of slides or picture plates to be exposed within a compact structure; another object of my invention is to provide novel auxiliary mechanisms whereby motion may be imparted to an exposed slide, such motion being either a rotary motion or an oscillating or rocking motion, my construction being adapted to combining in one device the means for obtaining either one of such motions or both of such motions for an exposed slide or plate.

Further objects and improvements contemplated by my invention hereinafter appear from my description and from the accompanying drawings wherein—

Figure 1 illustrates a side elevation indicating more particularly the manner of mounting the various rotating parts;

Fig. 2 represents a plan view thereof;

Fig. 3 represents a detail view, in elevation, of the oscillating and rotating mechanism for the slides;

Figs. 4 and 5 represent plan views of the slide frames together with the parts co-operating with the rotating and oscillating mechanism;

Fig. 6 represents a cross section of Fig. 4 taken on line 6—6 thereof;

Fig. 7 represents a cross section of Fig. 5 taken on line 7—7 thereof;

Fig. 8 illustrates the application of my construction for window display, the mechanism being incased by the metallic cover A 55 therefor, the cover having an opening for the protrusion of the projecting lens which registers with an opening beneath the platform of a shop window, for example, the lens being also in alinement with a mirror 60 placed at an angle of approximately 45° and which reflects the picture upon a semi-transparent medium whereby the picture may be seen from the outside of the window, or upon an opaque medium whereby the picture may be seen upon the surface on which it is projected;

Fig. 9 is a detail view of the manner in which the electric bulb beneath the lens may be secured in my construction. 70

In these drawings 1 represents the metallic frame work supporting various moving parts of my mechanism, said frame work comprising two pairs of parallel vertical beams 1^a—1^a, 1^b—1^b, two pairs of parallel cross beams 2^a and 2^b, two pairs of parallel horizontal beams 3^a and 3^b extending at right angles between the two pairs of vertical beams 1^a and 1^b and a pair of parallel horizontal beams 13^a intermediate of the 75 beams 3^a and 3^b. These beams being rigidly screwed or riveted together constitute the metallic frame and also serve as bearings as will hereinafter appear. A motor d is supported in the lower part of the frame upon 80 a cross beam secured between the beams 3^b—3^b and drives the longitudinally extending shaft 4, which shaft is provided with a worm gear 5, which in turn meshes with the teeth of a gear wheel 6 rigidly secured upon 85 a shaft 7 which is journaled in the lower pair of beams 3^b—3^b. This shaft 7 also carries the pinion 8 rigidly secured thereon, which in turn meshes with the teeth of the gear wheel 9 mounted to rotate about the 90 shaft 10, the said gear wheel 9 actuating the Geneva movement 9^a mounted upon the rotating shaft 9^b. This rotating shaft 9^b carries also a pair of sprocket wheels 11, the teeth of which engage the links of a pair of 95 100

continuous chains or slide carriers 12 traveling in unison with one another. The shafts 7, 10 and 9^b may, as shown, be conveniently mounted in the beams 3^b—3^b as shown in my drawings.

The pair of chains 12 are arranged to travel from the pair of sprocket wheels 11 to the pair of sprocket wheels 13 journaled in the pair of horizontal cross beams 13^a 10 and thence to the pair of sprocket wheels 14 journaled in the pair of horizontal beams 3^a, said several pairs of sprocket wheels being arranged in staggered relation to one another so as to provide for greater chain length than could otherwise be secured. From the pair of sprocket wheels 14 the chains 12 travel across the frame work in a direction longitudinally thereof to a pair of sprocket wheels 15, also journaled in the 20 pair of horizontal beams 3^a, thence to a pair of sprocket wheels 16 journaled in the pair of horizontal beams 13^a, thence to a pair of sprocket wheels 17, thence to a pair of sprocket wheels 18, thereafter again to be 25 taken up by the pair of sprocket wheels 11 in the continuous movement of said pair of chains.

Mounted upon the pair of chains 12 are a series of frames 19 adapted to carry the slides to be projected. The frames 19 are preferably made of sheet metal and detachable from the chains and are loosely or movably mounted thereon so as to follow the journey over the sprocket wheels without 35 flexing. In Figs. 4 and 5 I have shown these frames 19 as provided with hooks 20 which serve as pivots and engage the links of the chain 12. The frames 19 also are preferably provided with lugs 21 which 40 may be made of pliable metal so as to permit of the insertion or removal of the slides.

It will appear from the foregoing description, that, starting from their engagement with the sprockets 11, the pair of 45 chains and the series of picture slides are continuous in movement and are preferably arranged to cover a tortuous journey for the purpose of obtaining a greater chain length to enable a greater number of slides 50 to be carried thereby, within a compact space.

The illumination for the slides is supplied by an electric lamp 22 and its connections to a source of electric energy. This 55 lamp 22 may be supported by means of a bracket 23 fastened to one of the horizontal cross beams, as the cross beam 13^a, and is located beneath the condenser 24^a and the projector lens 24.

60 At the place in which the slides are in position for exposure I provide a mechanism for either rotating or oscillating one or more of them as desired, said mechanism comprising two shafts 25 and 26, the shaft 65 25 having a rotary motion and the shaft 26

having a rocking or oscillating motion. These shafts carry means to coöperate with means provided upon the slide frames for rotating or oscillating a slide or one of a pair of superimposed slides. The shaft 25 70 at its free inner end carries a pinion 27, the teeth of which are adapted to engage with the radially disposed teeth 29 of a supplemental or auxiliary slide frame 28, which is free to revolve in a groove 31 of a plate 30, 75 the plate 30 being adapted to fit into the frame 19 on top of the slide carried by said frame 19. The driven end of the rotary shaft 25 is connected by a belt-and-pulley connection 32, with a pulley 33 carried by the shaft 7 so that with the rotation of the shaft 7 a rotary motion will be transmitted to the shaft 25 and its gear wheel 27 and therethrough to the auxiliary rotating slide frame 28. The mechanism for oscillating, 80 in contradistinction to rotating, a slide or one of a pair of slides, comprises the shaft 26, the free inner end of which carries a friction disk 34 to engage a raised radially serrated or roughened surface 35 provided 85 upon an auxiliary slide frame 36 which may be mounted in a plate 30 similar to the mounting of the auxiliary slide frame 28. When the auxiliary slide frame 36 comes beneath the disk 34 its serrated raised surface will be engaged and actuated thereby. For the purpose of maintaining the friction surface 35 in operative position relative to the disk 34 and to limit the oscillating motion of the auxiliary slide frame 36, it is 90 desirable to provide a stop therefor such as the shoulder 36^a. The rocking movement of the shaft 26 is obtained by means of a crank 37 secured to the shaft 26, said crank 37 being actuated by means of a link 38, 105 connected to a disk 39 on a rotating shaft 40 which is connected by means of a belt-and-pulley connection 41 with the rotating shaft 25.

For further clearness I shall now describe 110 the train of operation of my construction.

The desired number of frames carrying the slides to be exposed are hingedly mounted upon the pair of chains 12. One or more of these frames may be equipped with 115 the auxiliary slide frame 36 or the auxiliary slide frame 28 or with both. The motor is then set into operation and its shaft 4 through the worm gear 5 rotates the gear 6 and the pinion 8 mounted upon the shaft 7; motion is thereby transmitted to the gear wheel 9 and its Geneva movement 9^a and to the sprocket shaft 9^b and its pair of sprocket wheels 11—11. The pair of chains or slide carriers 12 are set in motion and with them the frames 19 mounted thereon. Such of the slide frames 19 as are not equipped with the auxiliary slide frames 28 or 36 will travel into alignment with the condenser and the lens without engaging the auxiliary rotating 120 125 130

or the oscillating members 27 and 34. During the time of exposure of the slide, (the time of exposure being regulated by the Geneva movement) the slide will remain stationary. Assuming the succeeding frame 19 to be equipped with the auxiliary slide holder 28, said holder when it has reached the position for projection will be engaged by the pinion 27, the teeth of which will mesh with the radial teeth 29 provided upon the auxiliary slide holder 28, thereby rotating the same while at the location of exposure. The radial teeth 29 are of a height sufficient only to be engaged by the gear wheel 27 and will not be engaged by the friction disk 34 of the oppositely located reciprocating shaft 26 which friction disk is supported slightly above the plane of such radial teeth (see Fig. 3). The meshing of the pinion 27 with the teeth 29 will result in imparting rotation during the exposure of the slide carried by the slide frame 28, and if such slide be superimposed upon a stationary slide carried by the frame 19, relative motion to the design or picture carried by said frame 19 will be obtained. Assuming the next succeeding slide frame to carry the oscillating auxiliary frame 36 having the raised friction surface 35, the said frame when advanced to the location of exposure will carry the raised friction surface 35 into operative contact with the friction rocker disk 34. The rocker disk 34 will transmit to the auxiliary slide holder an oscillating movement during the exposure of the slide carried thereby and if a pair of superimposed slides be used, one stationary in the frame 19, the other oscillating in the frame 36, a relative movement between the slides will be obtained. Fig. 5 illustrates a slide exhibiting on the stationary slide the form of a person, an arm being omitted, while on the superimposed oscillating slide in the auxiliary film holder the arm and hand are placed in proper relation to said form, the two being so superimposed that the reciprocating movement for the auxiliary film holder will simulate the movement of a person brushing the teeth. For advertising purposes, for instance, this simulation of movement is particularly effective and is adaptable to every conceivable kind of merchandise or commodity. After the exposure, as regulated by the Geneva movement, is completed the next frame will be brought into position and so forth, until all the slides of the series will have been exhibited, when the series will be again repeated by the continuous journey of the chains.

While I have shown the mechanism of my apparatus in a position whereby the picture is projected upwardly, it will, of course, be understood that by tilting the mechanism the picture may be projected upon a side

wall, in which case the reflector can be dispensed with. It will also be understood that my construction may be made with various modifications without departing from the gist of the invention.

70

What I claim and desire to secure by Letters Patent is:

1. In a stereopticon apparatus the combination of a flexible continuous slide carrier, a slide frame carried thereby, means for imparting rotary motion to said slide frame when in its position of exposure and means for feeding said slide carrier to move the slide frame past its position of exposure.

75

2. In a stereopticon apparatus the combination of a flexible continuous slide carrier, a slide frame carried thereby, means for imparting motion to said slide frame when in its position of exposure and means for feeding said slide carrier to move the slide frame past its position of exposure.

80

3. In a stereopticon apparatus the combination of a pair of chains, a slide frame carried thereby, means for imparting rocking motion to said slide frame when in its position of exposure, a plurality of sprockets for actuating said chains and means for rotating said sprockets.

85

4. In a stereopticon apparatus the combination of a pair of chains, a slide frame carried thereby, means for imparting rotary motion to said slide frame when in its position of exposure, a plurality of sprockets for actuating said chains and means for rotating said sprockets.

90

5. In a stereopticon apparatus the combination of a flexible continuous slide carrier, a plurality of slide frames carried thereby, means for imparting rotary motion to a slide frame when in its position of exposure, means for imparting oscillating motion to another slide frame when in its position of exposure, and means for feeding said slide carrier to move the slide frames successively past the position of exposure.

100

6. In a stereopticon apparatus the combination of a continuous flexible carrier and a motor to operate the same, a main slide frame mounted upon said carrier, an auxiliary slide frame movably mounted on said main frame and mechanism for automatically imparting movement to one of said frames relatively to the other at the point of exposure.

110

7. In a stereopticon apparatus the combination of a continuous flexible carrier and a motor to operate the same, a main slide frame mounted upon said carrier, an auxiliary slide frame movably mounted on said main frame, means located in proximity to the position of exposure of said slide frames to impart movement to said auxiliary frame relatively to said main frame.

120

8. In a stereopticon apparatus the combination of a continuous flexible carrier and

125

130

- 5 a motor to operate the same, a main slide frame mounted upon said carrier, an auxiliary slide frame movably mounted on said main frame, means located in proximity to the position of exposure of said slide frames to impart movement to said auxiliary frame relatively to said main slide frame and connections with said motor to mechanically actuate said means.

10 9. In a stereopticon apparatus the combination of a continuous flexible carrier and a motor to operate the same, a main slide frame mounted upon said carrier, an auxiliary frame movably mounted on said main frame, a friction surface upon said auxiliary frame, means located in proximity to the position of exposure of said frames to engage said friction surface to impart movement to said auxiliary frame relatively to said main slide frame and connections with said motor to mechanically actuate said means.

15 10. In a stereopticon apparatus the combination of a continuous flexible carrier and a motor to operate the same, a main slide frame mounted upon said carrier, an auxiliary frame movably mounted on said main frame, a pinion upon said auxiliary frame, means located in proximity to the position of exposure of said frames to engage said pinion to impart movement to said auxiliary frame relatively to said main slide frame and connections with said motor to mechanically actuate said means.

20 11. In a stereopticon apparatus the combination of a continuous flexible carrier and a motor to operate the same, a main slide frame mounted upon said carrier, an auxiliary frame movably mounted on said main frame, a pinion upon said auxiliary frame, means located in proximity to the position of exposure of said frames to engage said pinion to impart movement to said auxiliary frame relatively to said main slide frame and connections with said motor to mechanically actuate said means.

25 12. In a display apparatus having a carrier, a series of slide frames mounted thereon, said frames bearing slides to be exposed at given points in the travel of said carrier, the combination of revoluble means of mounting a slide in its frame, a crown gear upon said slide, a gear to engage with said crown gear, a wheel on said gear, flexible driving means for said wheel, a motor, and mechanism intermediate said motor and said means to drive the latter.

30 13. In a display apparatus, in combination, a carrier chain, sprocket wheels engaged therewith, a drive gear wheel, a cam on a sprocket wheel, and a spur on said drive gear wheel to engage said cam and thus actuate said sprocket wheel to move said chain, a worm gear connected with said gear wheel; a slide frame mounted on said carrier, a slide revolubly mounted on said frame, a crown gear upon said slide, a gear wheel to engage with said crown gear, a wheel upon said gear wheel, a second wheel connected with said drive gear wheel, and means connecting said wheels to communicate motion from said drive gear wheel to said revoluble slide at a given point in the travel of the slide frame.

35

MAXIMILIAN KLAIBER.
